SIDETRACKING TOOL

William G. Brewster, Long Beach, Calif.

Application December 19, 1933, Serial No. 703,091

5 Claims. (Cl. 255—1)

This invention relates to a sidetracking tool, by means of which a hole can be drilled at a fixed angle from the vertical.

An object of my invention is to provide a tool which is adapted to be set in a known position in the hole and which will then drill ahead at a known angle from the vertical.

Another object is to provide a tool of the character stated which includes an angular casing non-rotatably held in the bored hole, and a bit attached thereto which will drill ahead at a known angle from the vertical.

Still another object is to provide a tool of the character stated which permits circulation there-thru, and which can be rotated while going into the bore, but the outer shell or casing of which is non-rotatably held when the bottom of the bore is reached.

Other objects, advantages and features of invention may appear from the accompanying drawing, the subjoined detailed description, and the appended claims.

In the drawing

Figure 1 is a side elevation of my tool.

Figure 2 is a longitudinal sectional view of the same.

Figure 3 is a fragmentary, longitudinal, sectional view of the universal joint and packing gland.

Referring more particularly to the drawing, my tool includes an outer shell or casing 1, the upper portion 2 of which is positioned at a fixed angle to the lower portion 3. The outer shell is either bent at the desired angle or the upper and lower sections are welded together at the desired angle.

A plurality of fins 4 project from the shell and these fins bite into the wall of the bored hole, when the bottom is reached, thereby non-rotatably holding the shell. The fins slide thru the formation when the tool is moving downwardly in drilling, and it is to be understood that this tool only starts the hole at an angle. Once the hole is started in the desired direction, my tool is removed and the usual bit is run into the hole, and the drilling continued.

A tubular stem 5 extends into the top of the shell 1 thru a packing nut 6. This nut screws into the top of the shell and prevents fluid from entering said shell at the top. A collar 7 screws onto the top of the stem 5 and the drill pipe screws into this collar so that my tool can be operated, as will be further described.

A ring 8 loosely encircles the stem 5 below the collar 7, and a plurality of spring arms 9

is attached to this ring. The arms 9 are attached at their lower ends to the shell 1. These arms are expanded outwardly against the wall of the hole to further assist in non-rotatably holding the shell 1, and also for the purpose of centralizing the shell in the hole when it is moving downwardly. The spring arms 9 are pressed outwardly against the wall of the hole by the downward movement of the stem 5 when the bottom of the hole has been reached. The reason for this downward movement will be subsequently described.

A pipe 10 extends into the bottom of the shell 1, and the bit 11 is secured to the bottom thereof. A packing nut 12 screws into the bottom of the shell and surrounds the pipe 10 for the purpose of preventing leakage at the bottom of said shell.

A universal joint 13 comprises a bowl 14 which is fixedly attached to the pipe 10. The method of attachment consists of a sleeve 15 which is welded to the bowl and to the pipe, the lower end of the sleeve forming a shoulder which abuts the nut 12, thus preventing the bit from moving downwardly and out of the shell.

A tube 16 is fixedly attached to the stem 5 by means of the sleeve 17 which is welded into the stem and the tube. The upper end of the sleeve 17 forms a shoulder which abuts the bottom of the nut 6, thus preventing the stem 5 from being pulled upwardly out of the shell or casing.

A hexagonal boss 18 is integrally formed on the lower end of the tube 16. The bowl 14 is also hexagonal internally so that the boss 18 will fit into it. The boss fits somewhat loosely and slidably in the bowl so that a universal coupling 35 is provided. A short nipple 19 extends downwardly from the boss 18 and accurately fits a counter-bore 20 in the bowl. The nipple 19 is formed with a head 21 and a ferrule 22 screws onto the boss 18, thereby holding the nipple in 40 position.

A yieldable packing 23 is positioned between the head 21 and the ferrule 22, thereby allowing lateral movement of the nipple relative to the boss 18.

A sheer pin 24 extends thru the shell 1 into the sleeve 17. When the bottom of the hole is reached, weight is applied to the stem 5. The boss 18 can slide downwardly in the bowl 14, and this movement may completely shear the pin 24. 50 When the pin has been sheared, the shell 1 may remain stationary while the stem 5 and the bit 11 are rotated.

The downward movement of the stem 5 also bows the arms 9 outwardly to hold said arms 55

tightly against the wall of the hole. The angular construction of the shell will also cause the fins 4 to be so positioned that they will bite into the formation, thus effectively holding the shell 5 against rotation.

The stem 5, the universal joint and the pipe 10 all have fluid passageways therethru so that circulating fluid can be conducted to the bit 11. As the drilling continues, the shell 1 will be forced 10 downwardly in the hole a distance of from ten to fifteen feet, more or less. Once the hole has been started in the desired direction, my tool is removed and the usual standard drill inserted. The standard drill will, of course, follow the hole 15 started by my tool.

Having described my invention, I claim:

1. A sidetracking tool comprising a casing, the lower end of said casing being at an obtuse angle 20 to the upper end of the casing, means on the casing whereby it is non-rotatably held in the hole, a mandrel extending thru the casing and rotatable therein, a bit on the lower end of said mandrel, a universal joint in said mandrel, a shear pin extending thru the casing into the mandrel, said 25 mandrel being longitudinally slidible in the casing whereby the shear pin is severed.

2. A sidetracking tool comprising a casing, the lower end of said casing being at an obtuse angle 30 to the upper end of the casing, means on the casing whereby it is non-rotatably held in the hole, a mandrel extending thru the casing and rotatable therein, a bit on the lower end of said mandrel, a universal joint in said mandrel, a shear pin extending thru the casing into the mandrel, said 35 mandrel being longitudinally slidible in the casing whereby the shear pin is severed, a ring journaled on the mandrel, spring arms attached at one end to the ring, the other end of said arms being attached to the casing.

40 3. A sidetracking tool comprising a casing, the lower end of said casing being at an obtuse angle

to the upper end thereof, a stem extending into the top of the casing and rotatable therein, a pipe projecting from the bottom of the casing and rotatable therein, a bit attached to the bottom end of the pipe, a universal joint attached to the stem 5 and operatively connecting the same with the pipe, packing glands at the top and bottom of the casing, and fins projecting outwardly from the casing whereby it is non-rotatably held in the hole. 10

4. A sidetracking tool comprising a casing, the lower end of said casing being at an obtuse angle to the upper end thereof, a stem extending into the top of the casing and rotatable therein, a pipe 15 projecting from the bottom of the casing and rotatable therein, a bit attached to the bottom end of the pipe, a universal joint attached to the stem and operatively connecting the same with the pipe, packing glands at the top and bottom of the casing, fins projecting outwardly from the 20 casing whereby it is non-rotatably held in the hole, said universal joint having limited longitudinal movement relative to the pipe, and a shear pin extending thru the casing into the stem.

5. A sidetracking tool comprising a casing, the lower end of said casing being at an obtuse angle to the upper end thereof, a stem extending into the top of the casing and rotatable therein, a pipe projecting from the bottom of the casing and rotatable therein, a bit attached to the bottom end 30 of the pipe, a universal joint attached to the stem and operatively connecting the same with the pipe, packing glands at the top and bottom of the casing, fins projecting outwardly from the 35 casing whereby it is non-rotatably held in the hole, said universal joint having limited longitudinal movement relative to the pipe, a ring journaled on the stem, and spring arms, one end of each of said spring arms being attached to the ring and the other end to the casing.

40 WILLIAM G. BREWSTER.
